(57) CLAIM

The ornamental design for a hair cover, as shown and described.

DESCRIPTION

FIG. 1 is a front view of the hair cover, showing the new design;

FIG. 2 is a right side view thereof;

FIG. 3 is a left side view thereof;

FIG. 4 is a rear view thereof;

FIG. 5 is top view thereof;

FIG. 6 is a bottom view thereof;

FIG. 7 is a front perspective view thereof;

FIG. 8 is another front perspective view thereof; and,

FIG. 9 is a bottom perspective view thereof.

The uniformly dashed lines shown on the surfaces of the hair cover in the drawings depict claimed stitching.

1 Claim, 4 Drawing Sheets
